REGISTERING TOURNIQUET APPLICABLE
FOR THE DETERMINATION OF BLOOD
PRESSURES

Elie J. La Liberte, Worcester, Mass.

Application September 27, 1937, Serial No. 165,860

1 Claim. (Cl. 128—2.05)

The principal object of this invention is to provide an arm or leg band for use as a registering tourniquet, such tourniquet also being practical for the determination of blood pressure.

5 Other objects of the invention are to make a bag of a thin membrane that will be flexible enough to transmit heart beats to the fluid contents of the bag but which will not stretch outwardly and at the sides when air or fluid is applied to the bag; to eliminate such stretching and thereby losing of impulses and pressure, the bag is reinforced on its outer surface in the form of a strong enough strip of fabric, or rubber, or a combination of both, which will serve such 10 purposes as, i. e., to preserve the flexibility of the outer portion of the bag so that it will take the contour of the limb so as to serve as means of attaching said band, and to provide on said strong strip on the outside, two nozzles, one, for 15 a bulb to provide air or fluid to the bag, the other, to connect with a pressure gauge for the purpose of determining the pressure and pulsations from the contents of the bag.

This band, being primarily a tourniquet, is 20 sturdy and narrow. If liquid is used as the content of the bag, the band can be made still narrower than represented by the figures given below, because of the better transmission of impulses due to the lesser compressibility of fluid 25 as compared with air.

Other objects and advantages of the invention will appear hereinafter.

Reference is to be had to the accompanying drawing, in which

35 Fig. 1 is a plan of the entire band laid out straight and not in operation;

Fig. 2 is a side view of the same with the air pressure gauge and bulb;

Fig. 3 is a plan of a somewhat modified form, 40 useful with a blood pressure apparatus;

Fig. 4 is a sectional view on the line 4—4 of Fig. 3;

Fig. 5 is a sectional view on the line 5—5 of Fig. 3, and

45 Fig. 6 is a view showing the instrument as applied to the arm.

Ordinarily, the medical profession has used an apparatus for the determination of blood pressure which is unsuited as a tourniquet and, from 50 a modern practical point of view, is awkward, cumbersome, and entirely unsuited to several useful applications that a more modern instrument of improved design could find. Ordinarily the rubber bag of the instrument now in use is about four inches wide and six and a half inches

long, enclosed in a cloth bag through which much of the impulse is lost. The cloth bag is wound around the arm or leg several times and serves rather suitably for thin limbs, but for short fat limbs, it has a tendency to roll and the disadvantage that it is likely to cover a vein, or a field, which is being tested for pressure or about to be opened for some surgical operation and in that case it is likely to cover also some of the sterile field. For that reason this arm band, which is 5 used for manometers, is seldom or never used as a tourniquet for the stopping of the venous flow and allowing the arterial blood to fill the vein in the arm or other limb before introducing a needle. It is seldom or never used as a tourniquet to shut off completely the arterial circulation in 10 case of amputation or other surgical procedures. The ordinary form of tourniquet has no thin membrane to transmit pressure to a bag nor is it equipped with a gauge, and it provides no means 15 of indicating whether the blood flow is shut off or not.

By this invention the old winding, cumbersome cloth bag is eliminated, though a covering may 20 be used to preserve the rubber in delaying oxidation and so prolong its life.

The inner surface of the band is formed of a narrow, very flexible, rubber membrane 10, formed of a compound which will be flexible enough to readily transmit the cardiac and pulse 25 action to the contents of the bag. The outer surface 11 of the bag is formed by a strip of rubber, or fabric, or a combination of both, of the same width, but of greater thickness, which strip 30 encircles the arm and is much more rigid and serves to prevent the impulses from being lost by the stretching of the bag. This fabric 11 is passed exactly once around the limb and its two 35 ends are secured directly and positively to each other. This can be done in any suitable way. 40 One way of doing this is to provide two series of button holes 12 on one end and a pair of buttons 13 on the other end to engage with the proper button holes. The buttons are buttoned 45 into the proper button holes to make the bag the right length, thus making it adjustable to that extent.

On the outside, or incorporated with, the fabric 11 are two nozzles 14 and 15, one for a bulb 16, 50 which is operated to provide air or liquid under pressure to the bag formed between the parts 10 and 11. The other nozzle connects with a pressure gauge 17. These two nozzles are located 55 preferably on the outer surface of the wall 11,

where they are held rigidly, and are located in any convenient place.

This bag may be two and a half inches wide or thereabouts and eight inches long, more or less. The inner membrane 10 is to be placed against the arm. It is made of a flexible gum compound approximately one thirty-second of an inch in thickness. The outer rubber 11 is to be made of a strip of less flexible rubber compound, 10 about one-eighth of an inch in thickness. This outer strip will be made in semi-elliptical shape, tapering to the inner membrane. The depth of the air or liquid pocket of the bag surface between the parts 10 and 11 may conveniently be 15 about one-quarter of an inch. Two tubes 19 and 20 are used to connect the nozzles with the air or liquid bulb and the gauge respectively.

This description is applied to the construction in Figs. 1 and 2 which is useful both as a blood 20 pressure appliance as well as a tourniquet.

The construction disclosed in Figs. 4 and 5 can also be used for both purposes, the operation being the same as in Figs. 1 and 2, but the construction differing in the fact that the bag shown 25 in Figs. 3, 4, and 5 is not designed to be secured at its ends by the buttons 13.

It will be seen that an arm band constructed, as stated, is not only more suitable for use with a manometer in a blood pressure testing apparatus but it is also better as a tourniquet than those now in use. This device will transmit to the registering instrument all kinds of records of cardiac action, which can be observed on the pressure gauge, the range of which will be very 35 much increased, thereby facilitating observation, giving information about the heart, the blood pressure and the condition of the artery.

This invention provides an accurate method of determining the shutting off of the venous flow, 40 this determination being possible by reason of the pressure gauge needle which will oscillate at the very onset of interference with the venous flow and the oscillation will increase somewhat until the venous flow is completely shut off. As soon as the oscillations are well established, the complete cessation of the venous flow is indicated.

An accurate method for the determination of the shutting off of the arterial flow is also provided by this invention, i. e. the interference of 45 the arterial flow is shown by the diminishing of oscillation of the pressure gauge needle, under increased pressure, and the complete shutting off

of the arterial flow by the cessation of oscillation of the pressure gauge needle under increased pressure.

By the use of a stethoscope with this invention, a thud will be heard with the interference 5 of the venous flow which will increase in intensity as the venous flow is completely shut off. On the contrary the diminishing of the thud with increase of pressure determines the interference with the arterial flow and the complete 10 elimination of the thud shows the arterial flow has been shut off. To accomplish this reaction, the stethoscope must be placed over the main vessels below the application of the arm band. The above data gives all information necessary 15 in case one wishes to gorge a vein for the introduction of a needle, as in blood transfusions, or the drawing of blood, and the like, or to shut off the flow of blood for amputations or other surgical operations.

This invention also determines more exactly the pulsation, and the venous and arterial pressures by eliminating much of the loss of impulses and pressure due to the present arm bands now in use.

This instrument is a compact and workman-like device which performs its function extremely well and is the only practical registering tourniquet known. It is easily made, requires little material, and performs its action better than 20 heretofore any other instrument has done.

Having thus described my invention and the advantages thereof, I do not wish to be limited to the details herein disclosed, otherwise than as set forth in the claim, but what I claim is:

As an article of manufacture, an air or fluid bag comprising an inner membrane of very thin material adapted to transmit pulsations from the blood flow and heart beat of the human body to the contents of the bag, said bag having an outer wall of substantially the same width, but of greater thickness and rigidity, spaced from the thin membrane, a nozzle supported in the thicker strip for attaching a bulb to introduce the pressure, and means mounted on the thicker strip for connecting a pressure gauge, said gauge indicating, by the oscillation of its needle, when the venous flow has stopped, and indicating, by diminishing oscillation, interference with arterial flow and finally, by cessation of oscillation, that 40 the arterial flow has stopped.

ELIE J. LA LIBERTE.
